CONTAINER EDGE SUPPORTABLE PAINTBRUSH HOLDER

Anthony Cortina, 56 Huntington St.,
New London, Conn. 06320

Original design application Feb. 26, 1967, Ser. No. 5,971.
Divided and this application Feb. 19, 1968, Ser. No.
10,735

Term of patent 14 years

U.S. Cl. D9—289
Int. Cl. D9—99

FIG. 1 is a side elevational view of a container edge supportable paintbrush holder, showing my new design;

FIG. 2 is a front elevational view of the holder of FIG. 1; and

FIG. 3 is a bottom plan view of the holder of FIGS. 1 and 2.

This is a division of my copending application, Ser. No. D. 5,971, filed Feb. 26, 1967.

The fragmentary container shown in broken lines in FIG. 1 are for illustrative purposes only.

I claim:

The ornamental design for a container edge supportable paintbrush holder, substantially as shown and described.
